UNITED STATES PATENT OFFICE.

FLORYAN WAJDA, OF EAST HAMMOND, INDIANA, ASSIGNOR OF ONE-HALF TO BARNEY J. GLINSKI, OF CHICAGO, ILLINOIS.

METALLIC TIE AND RAIL-FASTENER.

1,062,424.

Specification of Letters Patent. Patented May 20, 1913.

Application filed November 27, 1912. Serial No. 733,840.

To all whom it may concern:

Be it known that I, FLORYAN WAJDA, a subject of the Emperor of Austria-Hungary, residing at East Hammond, in the county of Lake and State of Indiana, have invented certain new and useful Improvements in Metallic Ties and Rail-Fasteners, of which the following is a specification, reference being had therein to the accompanying drawing, 10 This invention relates to a metallic tie and rail fastener, and among the principal objects of my invention are, first, that of providing a strong and durable metallic tie that can be easily tamped in a roadbed; second, 15 that of furnishing the tie with novel rail chairs and fasteners that prevent vertical and lateral displacement of rails mounted upon the tie, and third, that of providing a structure of the above type that is highly 20 efficient for supporting the great weight of rolling stock.

I attain the above and other objects by a mechanical construction that will be herein-after specifically described and then claimed.

Reference will now be had to the drawing, 25 wherein:—

Figure 1 is a side elevation of the tie and rail fastener, Fig. 2 is a longitudinal sectional view of the same, Fig. 3 is a plan of 30 the tie and rail fasteners, Fig. 4 is a similar view of a tie, and Fig. 5 is a perspective view of a rail chair.

Further describing my invention in detail with reference to the accompanying drawing, wherein like numerals denote corresponding parts throughout: 1 denotes a metallic channel-shaped tie that has the bottom thereof cut away, as at 2 to provide clearance for bolt heads, as will presently 35 appear. The inner side of the bottom of the tie, adjacent to the ends thereof, has pockets 3 to receive cushion blocks 4 that are preferably made of wood. These blocks extend into recesses 5 provided therefor in 40 the bottom of outer rail fasteners 6. The outer rail fasteners 6 engage the outer sides of rails 7 having the base flanges 8 thereof resting upon the top of the tie. The inner sides of the outer fasteners 6 are recessed, 45 as at 9 and provided with longitudinal cushioning strips 10 for rail chairs 11 that serve as inner fasteners. The rail chairs 11

have cushioning strips 12 supporting the base flanges 8 of the rails, and said chairs brace the inner sides of the rails 7 and are 55 interlocked with the outer rail fasteners by tongues 13 extending into the recesses 9. The rail chairs 11 have lateral extensions 14 provided with sockets 15 for tie rods 16 arranged centrally of the tie. 60

Seated in the top of the tie, intermediate the ends thereof is a top plate 17 that is locked in engagement with the bottom of the tie by vertical bolts 18 and nuts 19. The bolt heads are arranged upon the bottom of 65 the tie and said bolts extend through vertical grooves 20 formed in the sides of the extensions 14, also through openings 21 provided therefor in the top plates 17 and the bottom of the tie. 70

From the foregoing it will be observed that the rail chairs and outer fasteners are locked together and held against longitudinal displacement relatively to the tie and that the rails are braced in a manner that prevents the same from tilting or spreading. 75

What I claim is:—

In a metallic tie and rail fastener, the combination with rails, of a channel-shaped tie supporting the base flanges of said rails, 80 cushioning blocks arranged transversely within said tie adjacent to the ends thereof, outer rail fasteners arranged upon said blocks and engaging the outer sides of said rails, cushioning strips carried by said outer 85 rail fasteners, rail chairs arranged in said tie and bracing the inner sides thereof, said chairs resting upon the cushioning strips of said outer fasteners and having tongues interlocked with said outer fasteners, cushioning strips carried by said chairs and supporting the base flanges of said rails, tie rods connecting said rail chairs intermediate the ends of said tie, a top plate arranged upon said tie between said rail 90 chairs, and vertical bolts connecting said top plate to the bottom of said tie and engaging the side edges of said chairs. 95

In testimony whereof I affix my signature in the presence of two witnesses.

FLORYAN WAJDA.
